(57) CLAIM

We claim the ornamental design for a spiral package, as shown and described.

DESCRIPTION

FIG. 1 is a front, left perspective view of a spiral package showing our new design;

FIG. 2 is a left side view thereof;

FIG. 3 is a right side view thereof;

FIG. 4 is a front side view thereof;

FIG. 5 is a top plan view thereof;

FIG. 6 is a bottom view thereof; and,

FIG. 7 is a rear side view thereof.

The broken line portion of the figure drawings is included to show unclaimed subject matter only and forms no part of the claimed design.

1 Claim, 2 Drawing Sheets

FIG. 1

FIG. 2FIG. 3*FIG. 4*FIG. 5*FIG. 6*FIG. 7
